CLARENCE M. SYMONDS, OF SAN ANSELMO, CALIFORNIA.

CONTAINING-CAN.

934,370.

Specification of Letters Patent. Patented Sept. 14, 1909.

Application filed October 1, 1908. Serial No. 455,777.

REISSUED

To all whom it may concern:

Be it known that I, CLARENCE M. SYMONDS, citizen of the United States, residing at San Anselmo, in the county of Marin and State 5 of California, have invented new and useful Improvements in Containing-Cans, of which the following is a specification.

My invention relates to improvements in containing cans and especially that class 10 which is designed to contain hermetically sealed goods of any description, and which are known as "sanitary" cans; such cans being sealed without the use of solder, or other substance which may have deleterious 15 effect upon the contained fruit.

It consists in a means for closing and hermetically sealing the can after the contents of the can have been properly put or processed, and in readiness for the sealing.

Referring to the accompanying drawings for a more complete explanation of my invention,—Figure 1 is a side elevation, partly in section, of the can and top before assembling. Fig. 2 is an enlarged section of 25 the seamed top and can.

The ordinary method for preparing hermetically sealed goods for the market is to fill the cans, pass them through what is known as the "exhaust box", in which they 30 are heated so as to drive out any air that may be contained in the cans, then place the tops on the cans and pass them through the closing machine. In thus passing the open can through the exhaust box, the contents 35 swell more or less by reason of the heat, and project above the top of the can, so that this projecting portion being above the surface of the liquid with which the can is filled, becomes scalded, which is a serious objection, 40 especially in high grade fruit, and in the forcing of the top or cover on in the closing machine, the fruit is more or less crushed and bruised, and portions get between the flange of the can and the cover, and prevent 45 a perfectly air-tight joint being made.

In this invention the cans and covers are made with a peculiar interlocking flange so that the cover may be snapped on over the flange of the can body, after the can has been 50 filled, and before it goes into the exhaust box, and the cover, while being prevented from sealing off, leaves space enough to allow the proper exhaust or discharge of vapor, and at the same time prevents the 55 content from being scalded or bruised, and from getting between the flange of the can

and the body. It also avoids the handling of the cans while they are hot.

The cans which are formed in large quantities in the can factories and are shipped 60 to various points where they are to be used, ordinarily have a substantially radially projecting flange with which the cover, also properly flanged, will be "double-seamed" 65 as it is called, when the two are put together. These projecting edges of the can are easily 70 damaged in the process of shipment and handling, and when so damaged, there is great loss, because the heads will not close properly with them.

In my invention, the upper edge of the can A is turned over to form a rim 2, the outer edge of which is turned downwardly, as shown, and this down-turned edge forms 75 a resistant shape which will prevent its being damaged by rough usage.

The cover 3 is formed with an arched, annular rim 4 which is turned downwardly, thence bent inwardly and upwardly as shown at 5. This inturned edge 5 is of such 80 diameter that the cover can, by a little pressure, be caused to snap over the outwardly turned edge 2 of the can body, and thus engaged, it will not be possible to again remove the cover, but the engagement is a loose 85 one which allows any steam or vapor from the contents of the can to escape when the can is placed in the exhaust box after being filled. The contents of the can are also prevented from swelling and rising above the 90 liquid in which it is contained, and thus scalding is prevented. The contents are also prevented from extending over the edges of the can as the cover is already in place, and after the filling and exhausting have been 95 completed, the seam is formed by dies which are not here described, instead of using rollers by which the usual double seams of ordinary cans are formed. The closure may thus be completed without any handling of 100 the cans while hot, as they can be delivered automatically and directly from the exhaust box to the closing dies, and all the objectionable features heretofore mentioned, are avoided.

The invention may be applied to oval, square, or irregular cans as well as to round ones.

Having thus described my invention, what I claim and desire to secure by Letters Patent is—

1. In a containing can of the character de-

scribed, an outwardly and downwardly turned annular rim formed around the top of the can, a cover having a downwardly and inwardly turned peripheral edge adapted to snap into engagement and loosely interlock with the can flange to retain the cover in position.

2. As an article of manufacture, a can having an outwardly and downwardly turned flange around the top, a cover having a corresponding flange exterior to the flange of the top, said cover flange having an in-

wardly and upwardly turned extension, and said flanges adapted to slip one past the other and to snap into engagement when compressed, to form a hermetically sealed closing joint.

In testimony whereof I have hereunto set my hand in presence of two subscribing witnesses.

CLARENCE M. SYMONDS.
